UNITED STATES PATENT OFFICE

ROSA R. WELLSTATTER, OF NEW YORK, N. Y.

GARMENT

Application filed April 26, 1928. Serial No. 272,867.

This invention relates to improvements in garments and has special reference to costume slips, step-ins, and other forms of feminine undergarments.

5 For a better understanding of my invention I explain that so far, all such garments are made by joining two portions together, to form a tube (skirt) or the two portions are joined, each one separate, and these both 10 joined together in the crotch to make drawers or pants.

My invention has two portions of material; each portion can be made of one, or more pieces of material, cut straight or circular; but both portions must absolutely work together, from the start of making the garment until it is completely finished, to form both skirt and leg portions at the same time. The inner edges of these two portions mentioned have to overlap each other, 20 for a distance to form a crotch. This crotch part can be shaped a little for better fitting and then joined by stitching, etc. As described, the crotch part is cut in one piece 25 with the garment portions, and is suitable for sizes up to 38. For larger sizes, it is advisable to join the crotch on separately; then in this case, it is not absolutely necessary to have a seam at the center bottom of 30 the crotch, the separate crotch parts can be cut from one piece of material and these be joined on to the big portions in staggered relation. Both ways are suitable; answering 35 the same purpose and are included in the invention; only the joining seams in the crotch part are placed a little differently, otherwise, the garment is put together the same way, because after the separate crotch is seamed onto the inner side of each portion, then it is the 40 same two portions, or if the crotch is cut in one piece with the two garment portions which the width of the material only allows for smaller sizes. In making the garment, the one portion has to connect with the other 45 side of the other portion; and one portion has to overlap the open space left by the other portion; and also the inward ends of each portion must start on opposite sides of the body; for instance, if the one portion starts 50 in the front of the body adjacent the right

side, the other portion has to start in the rear of the body adjacent the left side; and vice versa, if the one portion starts on the left side front, the other portion has to start on the right side rear; and this is the same if 55 the crotch part is cut in one with the garment portion or added on. There is also one portion connected and joined together with the other portion in back and front a certain distance in the waistline as well as in the 60 crotch to form the leg portions. Another way of working out of different parts using two portions of material to make the garment is to have the crotch part joined on, only in 65 the back and in front cut in one piece, with the garment portion, or vice versa the crotch seamed on in front and not in back, in such cases the crotch seam must again be cross-ways.

One of the objects of this invention is to 70 provide a garment which may be either an outer garment or an undergarment and which will afford all the advantages and conveniences of a combination slip and step-in.

A still further object of the invention is to 75 provide a garment which may have an upper waistband adapted to surround merely the waist of the wearer or may have a bodice portion to cover the entire upper portion of the body and a skirt portion depending from the 80 upper portion which depended portion is provided with an intermediate portion adapted to extend between the limbs of the wearer and serve as a step-in by connecting the front and back parts of the inner portion together. 85

Another object of the invention is to provide a garment which may be formed of a single piece of material or of two pieces of material or, when occasion demands as in 90 the case of large garments, may be formed of more pieces of material suitably stitched together.

A still further object of the invention is to 95 provide a garment which is extremely simple in its construction, which is inexpensive to manufacture and which is highly useful. Convenience of arrangement of parts and attractive appearance are further desirable features which have been borne in mind in 100

the production and development of the invention.

With these and many other objects in view, which will more readily appear as the nature of the invention is better understood, the same consists in the novel construction, combination and arrangement of parts, which will hereinafter be more fully described, illustrated, and claimed.

10 The essential features of the invention involved in the carrying out of the objects indicated are susceptible to modification; but a preferred embodiment of the invention is shown in the accompanying drawings in 15 which:

Figure 1 is a perspective view showing one form of the garment in actual use upon the body of the wearer.

20 Figure 2 is a sectional view taken substantially along the line 2—2 of Figure 1.

Figure 3 is a perspective view of a modified form of the invention showing the garment detached from the body of the wearer and showing the step-in arrangement formed with 25 the crotch cut separate and attached onto the garment in staggered relation.

Figure 4 is a sectional view taken on the line 4—4 of Figure 3.

20 Figure 5 is a perspective view of one of 30 the pieces of material used to make up the garment.

Figure 6 is a similar perspective view of another piece of material used to form the garment.

35 Figure 7 is a perspective view showing the manner in which the two separate pieces are placed together to form the garment.

Figure 8 is a perspective view showing the 40 details of the crotch arrangement used in connection with the invention.

Referring to the accompanying drawings wherein similar reference characters designate similar parts throughout, the garment which may or may not have a waist bodice, 45 involves in its general organization an inner portion 10 and an outer portion 11. The garment may be formed from two portions of material or from a greater number of portions suitably stitched together. In Figure 2 50 the garment is shown as being made of two portions of material which are identical in construction, one portion being designated at 12 and the other at 13. These portions of material have their ends brought inwardly 55 and they are joined together as at 15 and the sides of the garment and the medial part of each portion taken in connection with the end of each other portion defines a space 16 through which the limbs of the wearer are 60 inserted. The part of each portion near the end of the same defines a crotch portion 17 which crotch portion is elevated with respect to the base of the garment as clearly shown in Figure 1. In this form of the invention it will be noticed that the end part 65

of each portion of material forms a flap. For the purpose of description, it may be stated that the garment is serpentine in its shape and the material passes between the limbs of the wearer at the point where the two portions are stitched together. 70

This garment has been described as admirably adapted for small sizes from 34 to 38. However, for large sizes above 38, it is preferable to form the crotch portions from an 75 additional strip of material as clearly shown in Figure 3 and Figure 4. In this form of the invention two portions at 20 and 21 are formed. These portions in the blank form may be rectangular or circular and they have 80 their immediate ends brought inwardly into the garment and joined to a crotch strip 22. While the crotch strip may be formed in any suitable manner and of any suitable material, it is preferable to form the same of 85 material that is slightly heavier in texture than the remainder of the garment. However, it is also within the scope of the invention to form this strip of elastic or rubber. As clearly shown in Figure 4, the serpentine 90 arrangement of the material is maintained in this form of the invention though it is slightly modified. The medial part of the portions 20 and 21 bear a relation to the crotch strip 22 that they form between themselves and the crotch strips a space for the limbs of the 95 user. In other words, the garment when worn, may be defined as commencing adjacent one side between the limbs and extending around the front of the wearer, and around the other side and to the rear overlapping each other on both sides. 100

Figures 5, 6, 7 and 8 are illustrative of the manner in which the garment is formed.

In Figure 5 there is shown a portion of 105 material pre-cut for forming a garment.

Figure 6 shows a similar portion of material also pre-cut.

These portions are placed together in the manner shown in Figure 7 and shaped for the 110 purpose of better fitting and then they are joined along the edges 30. It is preferable but not necessary to provide a cutaway shape 31 in each portion of material to form the elevated crotch portion. When an additional 115 crotch strip is to be employed, the portions are cut away as at 33 and are then joined to the crotch strip in staggered relation, thereby forming a garment that has an elevated crotch part. 120

It is obvious then, that I have provided a garment which is simple in its construction but, at the same time, is highly useful. I wish it understood that various changes in the details of the construction may be resorted to 125 without departing from the spirit of the invention, for example, the garment may be modified as to shape to conform to the ever changing trend of style. The garment may be made in the form of a costume slip, step- 130

in or drawers or may be in the form of an outer garment. But irrespective of these details of manufacture, the essential features of the invention are always preserved.

5 It must be emphasized that, while parts 12 and 13, for example, have been described as "pieces", that it is by no means essential or important that these be unitary strips. These pieces could of course be made of any desired 10 number of pieces, sewn together, without in any way affecting my invention, which is to be considered rather as directed to the crotch formation and the peculiar disposition of the skirt portion of my garment.

15 I claim:

1. A garment adapted to drape the body from substantially the waist line downwardly, comprising a skirt-like member adapted to encircle both limbs of a wearer, said skirt-like member having overlapping portions at both the front and the back at substantially the center line of the body, and means joining together only the front and the back inner overlapped portions below the tops thereof to form a crotch, which crotch in cooperation with the walls of the skirt-like member defines separate openings for the limbs, said crotch extending downwardly no lower than the bottom of the skirt-like member.

20 2. A garment adapted to drape the body from substantially the waist line downwardly, comprising a skirt-like member adapted to encircle both limbs of a wearer, said skirt-like member having overlapping portions at both the front and the back at substantially the center line of the body, and means joining together the lower ends of the front and the back inner overlapped portions to form a crotch, which crotch in cooperation with the 25 walls of the skirt-like member defines separate openings for the limbs, the outer of said overlapping portions extending below and over said crotch to conceal the same.

3. A garment adapted to drape the body 30 from substantially the waist line downwardly, comprising a skirt-like member adapted to encircle both limbs of a wearer, said skirt-like member having overlapping portions at both the front and the back at substantially the center line of the body, the overlapping and the overlapped portions being attached 35 together at their tops, the inner overlapped portions being substantially free along at least one of their upright edges, means joining together the front and the back inner overlapped portions below the tops thereof to form a crotch, which crotch in cooperation with the walls of the skirt-like member defines 40 separate openings for the limbs, the free upright edges of the front and the back overlapped portions being on opposite sides of the center line of the body and the outer of said overlapping portions being of a length to conceal the crotch.

4. A garment adapted to drape the body

from substantially the waist line downwardly, comprising a portion of material extending from a starting point in front of the body, around one side and across the back of the body, and another portion of material extending from the back of the body in overlapping relation to the first portion around the side of the body opposite to that around which the first portion extends and terminating in overlapping relation to the first portion in front of the body, the inner overlapped parts of said two portions being joined together below their tops to define a crotch.

5. A garment adapted to drape the body from substantially the waist line downwardly, comprising a portion of material extending from in front of the body in proximity to the center line thereof, around one side and across the back of the body terminating across said center line and another portion of material extending from the back of the body in overlapping relation to the first portion around the side of the body opposite to that around which the first portion extends and terminating in overlapping relation to the first portion in front of the body, the inner overlapped parts of said two portions being joined together below their tops to define a crotch.

6. A garment adapted to drape the body from substantially the waist line downwardly, comprising a portion of material extending from in front of the body, around one side and across the back of the body, and another portion of material extending from the back of the body in overlapping relation to the first portion around the side of the body opposite to that around which the first portion extends and terminating in overlapping relation to the first portion in front of the body, one overlapped part of each of said portions being disposed inwardly relatively to the body portion and said inwardly disposed parts being joined together in proximity to their terminal ends below the tops thereof to define a crotch.

7. A garment adapted to drape the body from substantially the waist line downwardly, comprising a portion of material extending from in front of the body, around one side and across the back of the body, and another portion of material extending from the back of the body in overlapping relation to the first portion around the side of the body opposite to that around which the first portion extends and terminating in overlapping relation to the first portion in front of the body, the lower ends of the inner overlapped parts of said two portions being joined together by means to form a crotch, and the outer of said overlapping portions extending below and over said crotch to conceal the same.

8. A garment of the type described comprising a bodice member and a skirt-like member carried by the bodice member, said skirt-

like member being adapted to encircle both limbs of a wearer and comprising overlapped portions at both the front and the back at substantially the center line of the body, and 5 means joining together only the front and the back overlapped portions below the tops thereof to form a crotch, which crotch in cooperation with the walls of the skirt-like member defines separate openings for the 10 limbs, the outer of said overlapping portions extending below and over said crotch to conceal the same.

9. A garment of the type described comprising a bodice member and a skirt-like 15 member carried by the bodice member, said skirt-like member being adapted to encircle both limbs of a wearer and having overlapping portions at both the front and the back at substantially the center line of the body 20 and extending to either side of said center line, the front and the back overlapped portions each being substantially free from the overlapping portions along at least one of their overlapped upright edges and said overlapped portions being connected together by 25 means in proximity to the lower ends of said free edges to form a crotch, which crotch in cooperation with the walls of the skirt-like member defines separate openings for the 30 limbs, said free edges of the overlapped portions being on opposite sides of the center line of the body, and the outer of said overlapping portions being of a length to conceal the crotch.

35 In testimony whereof, I have signed my name to this specification this 24th day of April, 1928.

ROSA R. WELLSTATTER.
